SHIP'S LIFEBOAT DAVIT

Humphrey George Taylor, deceased, late of Wolverhampton, England, by Harry R. Powell, Stourbridge, and Thomas H. Wolverson, Wolverhampton, England, administrators

Application October 18, 1956, Serial No. 616,832

Claims priority, application Great Britain
October 18, 1955

2 Claims. (Cl. 9—38)

This invention relates to ships' lifeboat davits and has for its primary object the provision of a new or improved construction and arrangement of davit for launching a ship's lifeboat from a stowage position between decks.

In a ship's lifeboat davit according to the present invention, each of the davit arms, from the outboard ends of which the lifeboat is suspended, has its inboard end pivotally connected to a carriage which is underslung from wheels or rollers engaging a normally substantially horizontal track which is straight and is fixed to the underside of the upper of the two decks, and the inner end of the davit arm is connected through gearing with a spur pinion mounted on the carriage and meshing with a fixed rack extending longitudinally of the track.

The arrangement is such that as the davit arms are allowed to swing down under their own weight and that of the suspended boat, by paying-out the usual control ropes from a winch, the geared connections of said arms with their respective pinions rotate the latter and cause them through their engagement with the toothed racks, to travel the carriages in an outboard direction along the horizontal straight tracks to positions in which the suspended lifeboat is clear of the ship's side and can be lowered into the water by paying-out the usual falls. Conversely, raising of the davit arms will cause their carriages to be travelled inboard along their tracks to bring the davit arms to inboard stowed positions below the upper deck.

The invention will now be described with reference to the embodiment shown, in end elevation, in the accompanying drawing.

Referring to the drawing, each davit arm 10 has its inboard end pivoted at 11 in a carriage 12 which is underslung from rollers 13, 14 engaging a substantially horizontal straight track 15 which is fixed to the underside of the upper of two decks 16, 17 between which the lifeboat 18, suspended from the outboard ends of the davit arms 10, is stowed when said arms 10 are in the fully inboard position as shown in full lines.

The inboard end of each davit arm 10 is provided with a toothed quadrant 19 operatively connected through a

2

train of gears 20, 21, 22, 23 to a toothed pinion 24 which is mounted on the carriage 12 and is in constant mesh with a toothed rack 25 fixed to and extending longitudinally of the track 15. The ratio of the gearing is such that a predetermined angular movement of the davit arm 10 causes the carriage 12 to travel along the track 15 from the extreme inboard position shown in full lines to the extreme outboard position shown in chain lines, or vice versa, said extreme positions being determined by stops 26, 27 fixed in the ends of the track 15.

The arrangement is such that as the davit arms 10 are allowed to swing down under their own weight and that of the suspended lifeboat 18, by paying out the usual control ropes 28 from a winch (not shown), the geared connections 20, 21, 22, 23 of said arms 10 with their respective pinions 24 rotate the latter and cause them, through their engagement with the toothed racks 25, to travel the carriages 12 in the outboard direction along the tracks 15 until arrested by outboard stops 26, in which extreme outboard position the suspended lifeboat 18 will be clear of the ship's side and can be lowered away by paying out the usual falls 29. Conversely, raising of the davit arms 10 will cause their carriages 12 to be travelled inboard along their tracks 15 to bring the davit arms 10 to the inboard stowed positions below the upper deck 16.

Having fully described the invention, what is claimed and desired to secure by Letters Patent is:

1. A davit for launching a ship's lifeboat from a stowage position between decks, comprising a normally substantially horizontal track fixed to the underside of the upper of the decks, a carriage suspended from said track and having rollers engaging the track, a davit arm having its inboard end pivotally connected to said carriage, a fixed rack extending longitudinally of the track, a spur pinion mounted on the carriage and meshing with said rack, and gearing connecting the inner end of the davit arm with said spur pinion.
2. A davit as set forth in claim 1, wherein the gearing includes a toothed quadrant on the inner end of the davit arm connected through a train of spur gears with the spur pinion, the ratio of the gearing being such that a predetermined angular movement of the davit arm will travel the carriage along the track from one extreme position to another, and carriage limiting stops at opposite ends of the track for determining said positions.
